UNITED STATES PATENT OFFICE.

GOTTFRID J. ANDERSON, OF GREENSBORO, NORTH CAROLINA.

CLOCK.

1,188,877.

Specification of Letters Patent. Patented June 27, 1916.

Application filed October 13, 1915. Serial No. 55,643.

To all whom it may concern:

Be it known that I, GOTTFRID J. ANDERSON, a citizen of the United States, and a resident of Greensboro, in the county of 5 Guilford and State of North Carolina, have invented a new and useful Improvement in Clocks, of which the following is a specification.

My invention is an improvement in clocks, 10 and the invention has for its object to provide a clock, wherein the usual spring and works are omitted, being replaced by electrically operated mechanism for moving the hands in accordance with the passage of 15 time.

In the drawings:—Figure 1 is a sectional view of a clock with the case in section, showing the parts in one position, Fig. 2 is a detail of Fig. 1, showing the parts in another position, Fig. 3 is a similar detail, 20 showing the parts in a third position, Fig. 4 is a view similar to Fig. 1, showing the parts in another position, Fig. 5 is a sectional view through the armature of the magnet, Fig. 6 is a detail of the contact mechanism, 25 Figs. 7 and 8 are sections on the lines 7—7 and 8—8, respectively, of Fig. 6, Fig. 9 is a front view of the clock with parts broken away, Fig. 10 is a section on the line 10—10 30 of Fig. 9, looking in the direction of the arrows adjacent to the line, and Fig. 11 is a detail of the pawl and ratchet mechanism for the minute hand.

The present embodiment of the invention 35 is shown in connection with a case 1, and the mechanism comprises the balance wheel 2, mounted on the balance staff 3, and having the usual hair spring 4, which is connected to the wheel to return the wheel when 40 it has been moved in a manner to be presently described.

Adjacent to the balance wheel is arranged a lever 5, the said lever having a hub 6, which is pivoted on the pivot pin 7, and the 45 free end of the lever is beveled as shown, and is adapted for engagement by a pin 8 on the hub of the balance wheel to move the lever in one direction.

The hub 6 of the lever has a radial arm 9, 50 extending at an obtuse angle with respect to the lever 5, and this arm is engaged by a pin 10 on a head 11, which is at one end of a plate spring 12. The other end of the plate spring has a base 13, which is secured to the 55 case by a screw 14, and a stop pin 15. The arm 9 engages the pin in a direction to move

the head and the spring 12 in one direction, and the movement of the head and spring in the opposite direction is limited by a fixed pin 16.

A jewel 17 is secured to the outer face of the head 11, and this jewel is segmental in form as shown, and the flat side of the jewel is adapted to engage a cam plate 18, which extends radially from a hub 19, pivoted to the casing by a pivot pin 20. The hub 19 is normally held in one position by a spring 21, which is secured at one end to the hub and at one end to the case as shown.

A lever 22 extends upwardly from the hub and this lever has its outer end beveled and is adapted to engage a wiper cam 23 on the shaft of the balance wheel. The jewel 17 normally engages above the cam plate 18 to prevent movement of the lever. A second 70 lever 24 extends radially from the hub 19 in the opposite direction from the lever 22, and this lever 24 engages a pin 25 on a head 26, on one end of a plate spring 27. This spring 27 is secured to the case in the same manner as the spring 12, as indicated at 28, and a stop 29 limits the movement of the spring and head in one direction. A segmental jewel 30 is secured to the outer face of the head and the flat edge of the jewel is adapted 75 to engage above a cam plate 31, extending radially from the hub 32, pivoted to the case on a pivot pin 33. A third lever 34 extends radially from the hub 19 at an acute angle to the lever 22 for a purpose to be presently 80 described, and the lever 5 has an extension 35 on the opposite side of its pivotal mounting, and the extension is engaged by a spring 36, the spring being secured to one end of the extension and at the other end to the case, and acting to return the lever 5 to the 85 full line position of Fig. 3, when the said lever has been released from the pin 8.

The lever 5 is limited in its movement under the influence of the spring 36 by means of a stop 37 on the case. The hub 32, before mentioned, has a radial lever 38, extending at an obtuse angle with respect to the cam plate 31, and this lever 38 engages at its free end a pin 39, on an angle arm 40, which is connected with the lever 41.

The lever 41 is pivoted at 42 to the case and the lever has an arm 43, which is provided with a notch or recess in its free end, and the notch or recess is engaged loosely 100 by a plate 44, extending longitudinally from the armature 45 of a magnet 46, mounted in

the case. The single arm 40 consists of two portions of unequal length, and the long portion is pivoted at its free end to the lever 41 near the pivotal mounting of the lever.

5 The short portion of the lever has a notch or recess 47 at its free end, and this notch or recess engages a screw 48 on the lever 41.

The angle arm 40 is adjusted with respect to the lever and is held in adjusted position 10 by the screw 48. The armature 45, before mentioned, is connected with a shaft 49 at the center of the magnet, the armature having an opening through which the shaft extends, and a spring 50 is arranged between 15 the magnet and the armature.

A bracket arm 51 is secured to the case above the armature, and the shaft 49 extends through an opening in the bracket arm. A set screw 52 is threaded through 20 the bracket arm into engagement with the upper face of the armature, and the set screw limits the upward movement of the armature.

The lower end of the pin 49 engages an 25 opening or recess in the upper end of the magnet as shown in Fig. 5, and the said shaft 49 moves with the armature.

A lever 53 is pivoted intermediate its ends at 54 above the armature, and the ends of 30 the lever are notched or recessed as shown. One end of the lever engages a pin 55 on the shaft 49, and the other end engages a pin 56 on a sliding rod 57, to which is connected a counter-weight 58. This rod 57 is guided 35 in its sliding movement by bracket arms 59 and 59^a, the said arms being secured to the case and having openings through which the rod extends.

When the magnet is energized and the armature moves toward the core of the magnet 40 the end of the lever 53 adjacent to the pin 49 will be moved downward and the counter-weight 58 will be lifted as shown in Fig. 4. When the armature is moved toward the 45 magnet under conditions to be presently described, the arm 43 will be swung, and the lever 41 will be swung in a direction indicated in Fig. 4.

When the cam plate 31 is released by the 50 swinging of the head 26 away from the stop 29 the normally opened circuit of the magnet is closed. This closing of the circuit is brought about by an arm 60, which is provided with a contact wheel 61, journaled on the free end thereof, and adapted to contact with a second contact wheel 62 on the head 63 of a plate spring 64. One end of this plate spring 64 is secured to the case as indicated at 65, in the same manner 55 as the springs 12 and 27 are connected, and stops 66 are provided at opposite sides of the head for limiting the swinging movement of the head. These contact wheels 61 and 62 are journaled to rotate on the arm 60 and the head respectively, and pawls 67 are

provided for preventing reverse rotation of the wheels, the said wheels being toothed as shown more particularly in Fig. 5.

A spring 68 is provided for the arm 60, and acts to move the wheel 61 into contact 70 with the wheel 62, the said spring being secured at one end of the case as indicated at 69, and at the other end to a radial lug 70, extending from the hub 32, before mentioned. Binding posts 71 and 72 are connected with the case, and lead wires from a suitable source of electrical energy are connected with the respective posts. A lead wire 73 leads from the binding post 71 to a connection with the plate spring 64, and a second lead wire 74 leads from the binding post 72 to the magnet. The other terminal of the magnet is connected by a lead wire 75 with the spring 68 before mentioned. When the cam plate 31 slips off 75 the jewel 30 the contact wheel 61 will immediately contact with the contact wheel 62, and the circuit of the magnet will be closed.

The arm 76 before mentioned, is pivoted at 77 on the extension 35 of the lever 5, and a set screw 77^a engaging the extension 35 has its head fitting over the arm to hold it flat against the lever. The arm 76 has an angular extension 78, and a spring 79 is arranged between this extension and the extension 35 of the lever 5, the spring acting normally to hold the arm 76 in contact with the adjacent edge of the lever 5. The arm 76 has an opening through which extends a laterally extending pin 80, from the lever 5.

The arm 76 at its free end extends a little beyond the free end of the lever 5, and the lever 5 is not quite long enough to be engaged by the pin 8. The arm 76, however, 105 extends far enough beyond the free end of the lever 5 to engage the pin 8. When the balance wheel is swung under the influence of the spring, because of the peculiar arrangement of the arm and the lever, the pin 110 will swing both arm and lever as indicated in dotted lines in Fig. 3.

The mounting of the various hubs and pivotal connections is the same as shown for the mounting of the hub 32 in Fig. 7. In 115 this figure the pivot pin 33 has its ends pointed, and they are held in conical recesses in the ends of bearing blocks or jewels 81, which are connected with the case. The bearings 81 may be of any insulating material to prevent electrical connection between the pivot pin 33 and the case.

The screw 82 which connects the end of the spring 68 with the case is insulated from the case by an insulating sleeve 83, having a flange 84, and the lead wire 75 is connected to the pin as shown. The plate spring 64 is also insulated from the case by an insulating block 85, as shown in Fig. 8. The spring 64 has a head 86, similar to the head 120

13 before mentioned, and this head is held to the insulating block by the connection 65, consisting of a screw and a pin.

The counterweight 58 steadies the action 5 of the magnet and relieves it from jar. Means is also provided for preventing over-banking of the balance wheel. This mechanism as shown in Figs. 1 and 4 is in the form of a lever 87, which is pivoted at 88, 10 and has a fork 89, at its lower end. A pin 90 on the hub of the balance wheel is between the arms of the fork and by its engagement with the said arms the pin limits the movement of the balance wheel. The 15 lever however, may yield under the impulse of the pin and the lever is provided with a diamond-shaped head 91 at the opposite end from the fork.

A plate spring 92 is secured to the case, as 20 indicated at 93, at one end and the other end has a head 94. This head engages the diamond-shaped head 91 of the lever 87, and while the head 94 may move to permit movement of the lever 87, yet the spring 92 25 will constrain the parts to return to normal position.

In Figs. 9 to 11 is shown the connection between the electromagnet armature and the operating mechanism for moving the hands 30 of the clock. The armature is provided with a laterally extending pin 95 on that face adjacent to the dial 96 of the clock, and this pin passes through a slot 97 in the supporting plate or disk for the mechanism shown 35 in Figs. 1 to 8, and bears against the outer end of a pawl lever 98. The pawl lever is pivoted at 99 to the plate or disk before mentioned, and a coil spring 100 normally presses the outer end of the lever upwardly. 40 A pawl 101 is connected to the inner end of the lever with a limited pivotal connection, and the movement of the lever 98 in one direction is limited by a stop 102. The pawl is pivoted at 103 to the lever 98, and the 45 outer end is beveled, and engages the teeth of a wheel 104, which is secured to a shaft 105.

The pawl 101 may swing in one direction to permit the return movement of the pawl 50 past the teeth 104, and it is normally held in engagement with the teeth on the forward movement by a plate spring 106, the spring being secured at one end to the lever 98 and bearing at the other against the pawl. A 55 pin 107 limits the swinging movement of the pawl under the influence of the spring.

The hour hand 108 and the minute hand 109 are secured to an arbor 110, and a shaft 60 respectively, the arbor being journaled on the shaft, and the arbor has a gear wheel 112, secured thereto behind the dial. A ratchet wheel 113 is secured to the shaft adjacent to the wheel 112, and the ratchet wheel 113 has rigid therewith a pinion 114. 65 This pinion 114 is in mesh with a gear wheel

116, which has rigid therewith a pinion 117, which meshes with the gear wheel 112 of the hour wheel, and the pinion and the gear wheel are secured to a shaft 118, journaled parallel with the shaft 111. This ratchet 70 wheel 113, before mentioned, is driven by a pawl lever 119, which is pivoted at 120 to the clock case.

A pawl 121 is pivoted to that end of the lever adjacent to the ratchet wheel, and the 75 free end of the pawl is beveled, and engages the teeth of the ratchet wheel. The pawl is pivoted to the lever as indicated at 122 and a spring 123 holds the pawl normally in engagement with the teeth on the forward 80 stroke of the pawl. A stop 124 is provided for limiting the movement of the pawl under the influence of the spring and the movement of the lever 119 is limited by stops 125 and 126, respectively. A spring 127 presses the 85 adjacent end of the lever 119 toward the stop 125.

The wheel 104 is provided with an eccentric pin 128, which once during each complete rotation of the wheel 104 will engage a 90 laterally extending lug 129 on an arm 130 integral with the lever 119 and extending longitudinally thereof. For each movement of the magnet armature 45 toward the cores of the magnet the lever 98 is swung and the 95 wheel 104 is moved a distance of one tooth. For each complete rotation of the wheel 104 the lever 119 is swung, and the minute wheel 113 is moved a distance of one tooth. The minute wheel, through the gear connection 100 114—116—117 and 112, drives the hour hand. The wheel 104 is prevented from reverse movement by a spring holding pawl 131. The lug 129 is a wedge shaped lug, having its small end toward the pin 128, the 105 arrangement being such that when the lever 119 swings in a direction to move the minute hand forwardly the pin 128 may pass the lug 129.

The operation of the device is as follows: 110 With the electric connections broken, the balance wheel would make two or three oscillations backward and forward, the lever 9 would release the cam plates 18 and 31, and as the armature would not lock the cam 115 plates, the position of the balance wheel and levers would be as shown in Fig. 3. The contact wheels would be in contact, and if now the lead wires should be connected with the source of energy, the armature 120 would cause the lever 22 to engage the wiper cam 23 and would swing the balance wheel to the right, that is, in the direction of the arrow indicated in Fig. 3. The cam plates 18 and 31 would lock on the jewels 17 and 125 30, and the electric contact would be broken. As the balance wheel moves toward the right, the pin 8 will pass the arm 76 of the lever 5, and when the balance wheel starts moving in the opposite direction, or toward 130

- the left, the pin 8 will eventually move the lever 5 as in Fig. 2, and as the cam plate 18 is released from the jewel 17, the arm 22 falls on the wiper cam 23, giving impulse 5 to the balance wheel on the flat or right side of the cam, and moving the cam and the balance wheel in the direction indicated by the arrows in Fig. 3. When, after having given the impulse, the lever 22 lifts the wiper cam, 10 the tension of the spring 21 causes the lever 24 to release the cam plate 31, and the circuit is closed through the wheels 61 and 62. The armature will cause the lever 41 and the pin 39 to lock the cam plates 18 and 31, 15 and the lever 22 takes its position for the next impulse without engaging the wiper cam which at this moment is still traveling toward the left, its position being almost opposite the point of the lever 5 as shown 20 in Fig. 4. As the balance wheel starts on its turn toward the right, the wiper cam 23 meets no obstructions, but passes the point of the lever 22 without touching the said point, the lever being at the right of the cam, 25 as shown in Fig. 1. As the balance wheel again moves toward the left, the same operation is repeated, the impulse being imparted by the lever 22, and this lever is in position to impart the impulse the moment the lever 30 9 releases the cam plate 18.

The balance wheel is moved under the impulse of the lever 22 by the never varying strength of the spring 21. The balance wheel in its movement to the left is free 35 from interference with any part, except for the lifting of the lever 5 as the wheel moves toward the left, and the slipping over the arm 76 by the pin 8. Because of the above facts, the time keeping quality of the clock 40 is of the highest order, the force running the balance wheel being constant and regardless of the strength of the electric current used. Only on the starting of the clock, that is, when the current is first connected 45 does the lever 22 start the clock from the beveled side of the wiper cam. Thus the clock is a self-starter, starting immediately on the connection of the cam. After the clock has been once started, the impulse is 50 imparted to the balance wheel from the spring 21, the electric current being used directly only to start the clock.

The release of the cam plate permits the hub 19 to swing under the influence of the spring 21, the arm 22 to give the impulse, and the arm 24 swings the spring 27 to release the cam plate 31. The spring 68 55 swings the hub 32 to cause the contact wheels 61 and 62 to contact, to complete the circuit 60 through the electric magnet and the armature 45 is immediately drawn toward the cores of the electro-magnet.

As the armature moves toward the cores, 65 as shown in Fig. 4, the lever 41 is swung in the direction of the arrow shown in Fig. 4.

The free end of the lever 41 swings the lever 19 against the resistance of the spring 21, in a direction to restore the cam plate 18 into engagement with the gear 17 and at the same time the pin 39 on the angle iron 40 70 swings the lever 38 to move the contact members 61 and 62 out of contact with each other. The pin 8 passes the arm 76, which swings away from the lever 5. As soon as the current is broken, through the armature 75 magnet the armature 45 moves away from the cores under the influence of the spring 50 and the ratchet wheel is moved a distance of one tooth.

The spring 21, in addition to its function 80 of holding the hub 19 in position, is the motive force, which acts on the levers attached to the hub 19, and the tension of the spring may be regulated by turning the center stud on the hub. The lever 22 is engaged by the 85 wiper cam at the opposite side from the bevel. It will be understood that the angle arm 40 could be made integral with the lever 41 if desired, and the position of the angle arm may be regulated by loosening the 90 screw 48.

The counterweight 58 is designed to steady the movement of the armature and to prevent shock or jar, and the said counterweight is an important feature of the invention for 95 this reason.

It will be evident from the description that the improved clock dispenses with the usual mechanism for returning the balance wheel, that is, with the usual works. The 100 hands are driven, and as a consequence, the time is measured by the electrical impulses in the electromagnet.

It will be understood that in a position of rest, that is, of perfect rest with the lever 105 released, the cam 23 would be about midway between the lever 22 and the lever 5. When now the armature is energized the lever 22 will start the balance wheel by engaging the curved side of the wiper cam. The wiper 110 cam occupies this position with respect to the parts only in a position of perfect rest with the current off as for instance, with the lead wires disconnected.

I claim:

1. In a movement for indicating time and in combination with the train of gearing, time indicating means and a ratchet mechanism for intermittently operating the train of gearing, an electromagnet, a circuit 115 closer included in circuit with the magnet, an armature actuated by the magnet to impart movement to the ratchet mechanism, a balance wheel, a primary lever actuated by the armature, a plurality of co-operating 120 spring actuated trip levers intermediate the primary lever and balance wheel and tripping means between the balance wheel and one of the spring actuated trip levers, and controlled by the movements of the balance 125 130

wheel to transmit movement from one lever to the other, one of such spring actuated trip levers controlling the circuit closer.

2. In a clock, the combination with the minute hand, the hour hand and the spring controlled balance wheel, of an electromagnet, an armature coöperating with the magnet, an open circuit in which the electromagnet is interposed, a switch in connection with the clock for controlling the circuit, a spring normally acting to close the switch, releasable means for restraining the closing of the switch, means controlled by the movement of the armature toward the magnet for swinging the balance wheel in one direction, and for returning the switch to normal position with the circuit open, means controlled by the movement of the balance wheel in the opposite direction under the influence of its controlling spring for releasing the restraining means for the switch, a connection between the clock and the minute hand of the clock for moving the said minute hand, and a driving connection between the minute hand and the hour hand.

3. In a clock, the combination with the minute hand and the hour hand, a driving connection between the minute hand and the hour hand for driving the hour hand synchronously with the minute hand, and a spring controlled balance wheel, of electrically controlled means for moving the minute hand at predetermined intervals, normally operated switch mechanism for controlling the electrically controlled means, means for restraining the operation of the switch controlling means, means in connection with the electrically controlled means and operated thereby for moving the balance wheel in one direction and for releasing the restraining means for the switch, and spring actuated trip means operated by the movement of the balance wheel to release the switch controlling means which are restored to normal position by the action of the electrically controlled means when the circuit is closed.

4. In a clock, the combination with the

minute and the hour hand, the driving connection between the minute and the hour hand for driving the hour hand in synchronism with the minute hand and the spring controlled balance wheel, of electrically controlled means for moving the minute hand a predetermined distance, normally operated switch mechanism for controlling the electrically controlled means, means for restraining the operation of the switch mechanism, a trip mechanism for the switch restraining means including a balance wheel, and means controlled by the electrically controlled means and operated when the minute hand is moved for moving the balance wheel in one direction, and for restoring the restraining means of the switch mechanism to normal position.

5. In a clock, the combination with the minute and the hour hand and the driving connection between the minute hand and the hour hand for driving the hour hand in synchronism with the minute hand, of a magnet having an armature, a connection between the armature and the minute hand for moving the minute hand predetermined distances when the armature moves toward the magnet, a normally open electrical circuit in which the magnet is interposed, switch mechanism for opening and closing the circuit, means acting normally to cause the switch mechanism to close the circuit, releasable means for restraining the closing of the switch, a balance wheel, a spring for moving the balance wheel in one direction, means operated by the balance wheel when moved under the impulse of the spring for releasing the restraining means, and means controlled by the movement of the armature toward the magnet for moving the balance wheel in the opposite direction and for restoring the restraining means to normal position.
